UNITED STATES PATENT OFFICE.

ALFRED C. GILBERT, OF NEW HAVEN, CONNECTICUT, ASSIGNOR TO THE A. C. GILBERT COMPANY, OF NEW HAVEN, CONNECTICUT, A CORPORATION OF CONNECTICUT.

DESIGN FOR A MOTOR-FAN GUARD.

58,903.

Specification for Design.

Patented Sept. 6, 1921.

Application filed April 27, 1921. Serial No. 465,007. Term of patent 14 years.

To all whom it may concern:

Be it known that I ALFRED C. GILBERT, a citizen of the United States, residing in New Haven, New Haven county, Connecticut, have invented a new, original, and ornamental Design for a Motor-Fan Guard, of which the following is a specification, when taken in connection with the accompanying drawing.

In the drawing:

Figure 1 is a front elevation of a motor fan guard embodying my new design; and

Fig. 2 is a side view of the same, a portion of the motor to which the guard is attached being shown in dotted lines.

What I claim is:

The ornamental design for a motor fan guard, substantially as shown.

ALFRED C. GILBERT.
